UNITED STATES PATENT OFFICE.

JOHN J. FENTON, OF MONTREAL, QUEBEC, CANADA.

SEWING-MACHINE ATTACHMENT.

Application filed March 17, 1923. Serial No. 625,858.

To all whom it may concern:

Be it known that I, JOHN J. FENTON, a subject of the King of Great Britain, and resident of the city of Montreal, in the Province of Quebec and Dominion of Canada, have invented certain new and useful Improvements in Sewing-Machine Attachments, of which the following is a full, clear, and exact description.

10 This invention relates to new and useful improvements in picot edge cutters for sewing machines, and the object of the invention is to provide a simple, inexpensive and adjustable cutting mechanism for sewing machines.

Another object is to provide a device which will be permanently attached to the presser foot and which will be easily put out of action when not required.

20 In my invention, I provide a crosshead to which is attached the presser foot, within which operates a pair of scissors for cutting the material after it has been stitched or hemmed, the whole operation being done in one operation of the machine. The scissors are oscillatably mounted in the crosshead and one leg is adapted to be operated by a cam against a spring to hold said leg when in the operating position. The other leg is hingedly connected to the presser foot and is adapted to be operated by the movement of the piercer bar, through the medium of a lever mounted on the crosshead and connected to an extension of the scissors leg.

30 The link is provided with a slotted connection to allow the length of the cut to be adjusted. The link is also provided with an adjustable sliding connection to the operating lever and is so mounted that the link can be placed in an inoperative position, said link being placed on the dead centre. The crosshead is securely fixed to the presser foot bar of the sewing machine and may be slidably mounted in the head of the machine, so that it can be raised to allow for the insertion of the material to be operated upon.

In the drawings which illustrate the invention:—

50 Fig. 1 is a front elevation of the device. Fig. 2 is an end elevation of the cutting mechanism. Fig. 3 is an elevation of the sliding connection between the operating link and the operating lever.

Fig. 4 is a plan view of Figure 3.

Referring more particularly to the drawings, 11 designates the head of a sewing machine in which is slidably mounted the presser foot bar 12, the piercer bar 12^a and the needle bar 13, which are operated in the well known manner. Attached to the presser foot bar is the crosshead 14 by means of the screw, which engages with the presser foot bar passing through the crosshead aperture 15. Oscillatably mounted on the crosshead are the presser feet 16, the pins 17 passing through both the presser feet and the crosshead. Between the presser feet 16^a and 16^b the scissor points 18 and 19 oscillate about the pin 20 passing through the bracket 14^a secured to the presser bar 12. The scissors arm 18 is provided with an extension 21, which is yieldably attached by a spring 21^a to a lug 22 cast integral with the bracket 14^a. A cam-shaped operating lever 23 is pivotally mounted on the bracket 14^a and is provided with a grip 24 for easy operating of the cam. The cam engages with the scissors arm extension 21 and acts in conjunction with the spring to release or put into action the scissors point 18. The scissors point 19 is provided with an operating arm 25, which extends beyond the fulcrum pin 20, and attached thereto is an adjustable link 26, which is made in two parts adjustably connected together by the slot and screw connection 27 and 28. One end of the link is pivotally connected to the arm 25 of the blade 19 and the other end of the link is pivotally connected to the pin 34 which is adjustably mounted in the grooved guideway 32 of the lever 29. The operating lever 29 is pivotally mounted in an extension 14^b of the bracket 14^a. One end of the lever is provided with a slot 30, the sides of which are in operative connection with the piercer bar, so that on the movement of the said piercer bar the lever pivots about the pin 31 passing through the extension 14^b. The other end of this lever is slidably or adjustably connected to the link 26 as before mentioned said lever being provided with a grooved guide 32, within which the head 33 of the pin 34 slides. A wing or thumb nut 35 is provided for the pin 34, so that quick and simple adjustment can be made and the head 33 moved along the guides.

The operation of the device is as follows:—

The presser foot is raised and the mate-

rial to be operated upon is placed between it and the bed plate of the machine. The presser foot is then dropped and the machine worked in the well known manner.

- 5 The scissors point 18 is released by moving the cam-shaped lever 23 and allowing the spring to pull the extension, so that the said point is in the operative position. The scissors point 19 is operated by the simple lever 10 and link construction by means of the movement of the piercer point or bar. Adjustment can be made to suit through the slotted connection between the component parts of the link 26. To put the scissors in the 15 inoperative position, the action is very simple. The cam is pressed against the extension 21 of the scissors point 18 whereby the latter is raised clear of the material. The thumb nut 35 is loosened and the pin 34 20 pushed along the guide 32 between the grooves until the centre of the pin 34 coincides with the centre of the pin 31, which is the pivoting centre of the operating lever 29. As this position is reached, no movement is transmitted to the scissors point 19 25 or the link 26 and the scissors point 19 is clear of the material.

Slight modification may be made in the construction of the various members of the 30 scissors gear without departing from the spirit of the invention.

To facilitate the working of the device, an automatic scissors controlling mechanism is fitted to the cross-head. It has been found 35 that operators may forget to use the cam for lifting one of the scissors points clear of the material when raising the presser foot and thus material may be torn or damaged. To overcome this difficulty, I provide a bar 40 35^a working in a guide 36 attached to the presser foot bar. The bar is fitted with a compression spring 37 between a head 38 and the guide 36. At the other end of the bar, an adjustable finger 39 is fitted. The 45 end 40 of the finger 39 is bent inwardly and works in a slide or slot 41 formed in the bracket 14^a and engages with the extension of the scissors point 18.

The operation of this mechanism is as follows;—When the presser foot is raised, the 50 head 38 engages with the head 11 of the sewing machine and presses the bar 35^a downwardly, thus bringing the end 40 of the finger 39 into contact with the scissors point extension 21, and thereby raises said point clear of the base of the presser foot, allowing for the easy extraction of material from the machine. When the presser foot is lowered, the bar 35^a is raised by the 55 spring 37 and allows the tension spring 21^a to bring the scissors point below the presser foot and into the cutting position.

Having thus described my invention, what I claim is;—

- 65 1. In a device of the character described,

a presser foot bar, a cross-head attached thereto, presser feet attached to said cross-head, a bracket attached to the presser foot bar, a pair of scissors pivotally attached to the bracket and positioned between the 70 presser feet, extensions on said scissors, means to hold one of the scissors points in or fixedly out of the cutting position, and means connected to the other part of the scissors to oscillate or hold it in an inoperative position, 75 said means comprising a grooved and slotted, pivotally mounted lever on the bracket, the slotted end to be in engagement with the piercer bar of a sewing machine, the other end of the lever slidably connected to the scissors extension, the centre of said slideable connection to coincide with the pivot of the lever when in the inoperative position.

2. In a device of the character described, a presser foot bar, a crosshead attached thereto, presser feet attached to said crosshead, a bracket attached to the presser foot bar, a pair of scissors pivotally attached to the bracket and positioned between the presser 80 feet, extensions on said scissors, means to hold one of said scissors points in or fixedly out of the cutting position, means to oscillate the other point of the scissors or to hold it in the inoperative position, said means comprising a link, a lever oscillatably mounted on said bracket, one end of said lever having a slotted end in engagement with the piercer 85 bar of a sewing machine, the other end of said lever being provided with a grooved guide, and a large-headed pin slidably mounted in said guide and through the link, so that the pin may be slid into the inoperative position with its centre coinciding with the 90 centre of the pivot of the lever.

3. In a device of the character described, a presser foot bar, a crosshead attached thereto, presser feet oscillatably mounted in said crosshead, a bracket attached to the presser foot bar, a pair of scissor blades, a pin passing through the bracket and the scissor blades, extensions on the end of said scissor blades, a lug on the upper part of the bracket, a tension spring connection between one 100 of said extensions and the lug, a hand operated cam mounted on said bracket and adapted to hold one of said scissor blades in the inoperative position, a link, a slot in said link, means for securing the link to the other scissor blade extension, a lever with one end slotted and freely connected to the piercer bar, the other end of said lever being grooved to form a guide, a pivot pin passing through the lever and the bracket, and a connecting pin for connecting the link and the lever, 105 sliding in said grooved guide and adapted to allow the connecting pin centre to coincide with the pivot pin centre when the scissors 110 are in the inoperative position.

4. In a device of the character described, a presser foot bar, a crosshead attached there- 115

to, presser feet oscillatably mounted in said crosshead, a bracket attached to the presser foot bar, a pair of scissor blades, a pin passing through the bracket and the scissor blades, extensions on the end of said scissor blades, a lug on the upper part of the bracket, a tension spring connection between one of said extensions and the lug, a hand-operated cam mounted on said bracket and adapted to hold the spring-controlled scissors extension in inoperative position, a link, a slot in said link, means for securing said link to the other scissor blade extension, a lever having one end slotted and freely connected to the piercer bar of a sewing machine, the other end of said lever being grooved to form a guide, a pivot pin passing through the lever and the bracket, a connecting pin for connecting the link and the lever, sliding in said grooved guide and adapted to allow the connecting pin centre to coincide with the pivot pin centre when the scissors are in the inoperative position, and automatic means to hold the scissors point above the base of the presser foot when said foot is raised to clear the material.

5. A device according to claim 4, in which the automatic means to hold the scissors point above the base of the presser foot comprises a guide attached to the presser foot bar, a headed pin passing through said guide, a compression spring between the guide and pin head, and an adjustable finger attached to said pin and adapted to engage with one of the scissor blades when the presser foot is raised and to clear said blade when the presser foot is lowered.

In witness whereof, I have hereunto set my hand.

JOHN J. FENTON.
